WINCH

John Hart Wilson, Wichita Falls, Tex.

Application June 7, 1946, Serial No. 675,220

4 Claims. (Cl. 254—187)

1

This invention relates to rotary well drilling rigs and the like, and more particularly to the hydraulic braking installation associated with the hoisting mechanism.

In early drilling equipment, whether in connection with the bull wheel, the calf wheel, or the sand reel or draw-works drums, the retarding or checking of the fall of loads into the well was effected only by mechanical friction brakes, usually of the band brake type, under the control of the operator. Such brakes were subject to rapid failure due to excessive wear, and in these days of deeper wells and heavier equipment, they are seldom employed alone in lowering drill pipes and the like into the wells.

To meet the need for an effective means for relieving the brakes of such wear and liability of breakage due to the great weights handled in drilling a deep well, and of the damage caused by the high speeds of operation, there was developed the hydraulic fluid brake which, when coupled to the drum shaft, serves to retard the free fall of the string of drill pipe, or other loads, and to absorb the great amount of energy developed.

In drilling a well, it becomes necessary at times to pull the string of drill pipe—as for example when the drill bit must be renewed or repaired—and then to replace the drill pipe in the bore hole. The lowering or replacement of the string of pipe is referred to as “going in the hole” and the raising and removal of the pipe is called “coming out of the hole.”

The operation of going in the hole consists of the alternate lowering of the string of pipe the distance equal to the length of the newly coupled stand of pipe, and lifting the empty travelling block to attach another stand to the string. Obviously, the necessity of braking or retarding the descent of the load by other means than the usual winch controlling band brake arises only when the drill pipe is being lowered, and it is desirable that some means be provided for disconnecting the supplemental braking or retarding device when the cable is being wound on the drum in raising the block. Otherwise, unnecessary power would be expended in working against the extra load imposed by such retarding means.

When coming out of the hole, the winch drum is alternately driven to wind the cable to raise the string of pipe in order to detach the successive stands, and then allowed to run free while the cable is unwound to permit the empty block to descend to be connected again with the drill pipe. It will be readily understood that during

2

neither of these operations involved in coming out of the hole, is there any necessity nor desirability for the use of supplemental braking or retarding means. When the pipe is being raised, the imposition of the additional resistance of a brake would be a foolish waste of power; and during the alternate operation of lowering the travelling block, the weight of the empty block ordinarily would not be enough to rotate the winch drum to unwind the cable if the drum were retarded by any braking means, and power would have to be applied to run the drum in the reverse direction.

It is therefore an object of the present invention to provide a novel and improved hoisting system particularly adapted to use in connection with the drilling of oil wells, in which a hydraulic retarder or brake is coupled to the winding drum or winch, by means of both a manually operated clutch and a one-way or overrunning clutch, whereby the brake mechanism may be automatically released when the drum is rotated to raise the load and may be manually connected and disconnected at will when it is desired that the drum rotate freely in the unwinding direction. In the preferred embodiment, the manual clutch—of the jaw clutch type—and the overrunning clutch are operatively disposed in series, with the manual clutch nearer to the drum or other hoisting means.

Applied specifically to the well drilling operation the functioning of the clutches or couplings is as follows:

- A. Going in the hole
  - (1) Lowering the pipe
    - Manual clutch engaged
    - Overrunning clutch automatically engaged
  - (2) Raising empty block
    - Manual clutch engaged
    - Overrunning clutch automatically disengaged
- B. Coming out of the hole
  - (1) Raising the pipe
    - Manual clutch disengaged
    - Overrunning clutch thus disconnected
  - (2) Lowering empty block
    - Manual clutch disengaged
    - Overrunning clutch thus disconnected

The novel combination of controls provided by the invention is much more efficient and adaptable than any arrangement in which either of

the two clutches is used alone. The use of an overrunning clutch only would not permit the accomplishing of operation B (2) without the application of power to drive the drum in the reverse direction, and the use of a manually operated jaw clutch alone is subject to serious objections and positive dangers.

First, it will be realized that in lowering the string of pipe stand by stand, the operator would have to engage the jaw clutch each time a stand of pipe is lowered and disengage the clutch whenever the block is raised to connect with the next stand of pipe. Since there may be as many as one hundred and fifty or more stands of pipe to be lowered into a deep well, it will be seen that approximately three hundred operations would be required in engaging and disengaging the jaw clutch in accomplishing this purpose.

Then again, in case of the use of a jaw clutch alone, if the operator should fail to disengage the clutch when the hoisting machinery is driven to raise the tackle, there would be an unnecessary waste of power in driving the hoist against the inertia of the brake. The most serious objection of all, however, to the sole use of the manually operated jaw clutch lies in the frequent failure of the driller, through negligence or accident, to engage the jaw clutch at the proper time before the lowering is commenced, and then when he attempts to engage the clutch while the hoist drum is paying out the cable at a high speed and the hydraulic brake is idle, serious breakage and consequent loss of drilling time ensues. The rotating drum weighs several thousand pounds and the motor of the hydraulic braking mechanism may weigh, or offer a resistance of, from 1500 to 2000 pounds. The shock caused by the engagement of the jaw clutch under these conditions is so great that it is not unusual for the drum shaft key to be sheared, or other serious damage caused to the braking system or other parts of the drilling rig.

Other objects and features of novelty, including certain details of construction of the brake system, will be apparent from the following specification when read in connection with the accompanying drawings in which one embodiment of the invention is illustrated by way of example.

In the drawings,

Figure 1 is a fragmentary view of a rotary drilling rig, showing the hoisting mechanism and the braking system in elevation;

Figure 2 is a view in elevation, and on an enlarged scale, of the hoisting mechanism and the brake system;

Figure 3 is a vertical sectional view through the aligned drum and brake shafts, showing the couplings and clutches in considerable detail;

Figure 4 is a transverse sectional view through the one-way clutch, taken on line 4-4 of Figure 3;

Figure 5 is a transverse sectional view through a portion of the shaft coupling as taken on line 5-5 of Figure 3; and

Figure 6 is a transverse sectional view through the jaw clutch and taken on line 6-6 of Figure 3.

Referring more particularly to Figure 1 of the drawings, it will be seen that the conventional derrick for the rotary drilling rig is indicated at 10, and is provided with a base 11 upon which the skid 12 of the hoisting assembly is adapted to rest. Spaced pedestals or bearing supports 14 are carried by the skid 12 and these in turn provide sturdy and rigid mountings for the bearings 15 of the drum shaft 16. The drum 17 keyed upon

the shaft 16 is of conventional type and is driven through the sprocket and chain transmissions, indicated at 18 and 19, from suitable sources of power (not shown).

5 The cable 20 is wound upon the drum and passes over the crown block sheaves 21 at the top of the derrick 10, and supports a travelling block 22 from which is suspended a swivel 23, which serves to support the upper end of a string of drill 10 pipe 24. As thus far described, the parts of the rig are conventional.

The end of the hoist drum shaft 16 which extends toward the left in Figures 1, 2, and 3 of the drawings, is provided with splines as at 25 where- 15 by it is keyed to the axially movable element 26 of the jaw clutch 27. This movable element 26 is adapted to be engaged with the complementary element 28 of the jaw clutch by means of the hand lever 29, the lower end of which is pivoted 20 as at 30 to a projection 31 on the pedestal 14.

As shown most clearly in Figure 3 of the drawings, driven element 28 of the jaw clutch assem- 25 bly 27 is mounted on an extension 32 of the drum shaft 16 and is relatively rotatable with respect 20 to said shaft by virtue of the ball bearings 33, this bearing assembly being covered by the cap or plate 34 bolted to the jaw member 28.

The element 28 of the jaw clutch 27 is provided 30 at its left hand edge with a sprocket portion 35 which mates with a similarly formed sprocket 36 formed on an intermediate coupling member 37. An endless sprocket chain 40 surrounds these two adjacent sprocket elements. At the left hand edge of the intermediate coupling element 37 35 there is formed another sprocket wheel 41, which is connected by means of an endless chain 42 with the sprocket 43 formed on the annular hub member 45. This latter member 45 is secured to the outer clutch member 46 of the one-way clutch 40 device 47, by means of the bolts 48. The inner hub member 50 of the one-way clutch 47 is keyed 45 as at 52 to the shaft 53 which extends into the hydraulic brake or retarding device 55 and is secured to the rotary element thereof.

45 The flexible self-aligning coupling 28, 37, 45 inclusive is preferably enclosed in a housing 70 which may conveniently be formed in two sections 71 and 72 as clearly indicated in Figures 3 and 5 of the drawings. The sections 71 and 72 50 are preferably flanged as at 73 and recessed as at 74 so that the securing bolts 75 may be readily applied. The end flanges 76 of the housing 70 may be provided with seals 77 where they fit cylindrical portions of the elements 28 and 45.

55 Referring now to the details of construction of the one-way clutch 47, the outer member 46 of this device is mounted for rotary movement with relation to the inner hub element by means of the pair of ball bearings 56, one arranged upon either 60 side of the central portion of the clutch. A plate 58 secured by the bolts 57 is provided at the side of the outer member 46 opposite to the one to which the member 45 is secured, and the oil seal rings 59 and 60 seal off the elements 58 and 45 65 respectively with respect to hub portions formed on the inner clutch member 50. By this means lubricant may be retained within the clutch.

The principal operative portions of the clutch 70 are best seen in Figures 3 and 4 of the drawings and they comprise the rollers 62 which are received within the cylindrical bore of the outer member 46 and the inclined cams 63 of the inner member 50. A cage 64 serves to retain the rollers in spaced relation around the periphery of the clutch. The cage 64 is permitted limited move-

ment with respect to the inner member 50 and is connected thereto by means of the springs 65, one end of each of the springs being connected to an ear 66 secured to the cage 64, and the other ends of the springs are secured to hook elements 67 carried by the inner member 50. The tension of the springs 65 serves to urge the rollers 62 up the inclines of the cam portions 63 and thus when the outer or driving element 46 of the clutch is rotating in the direction of the arrow A the rollers 62 will be urged up the inclines 63 into wedging engagement between the outer driving element 46 and the inner driven element 50, and the brake shaft 53 will be rotated within the hydraulic brake chamber and the retarding effect will be attained.

Upon reversal of the direction of rotation of the outer driving element 46 of the clutch, however, the rollers 62 will be moved down the inclined cam faces 63, against the urging of the springs 65, and the outer member will rotate while the inner element remains stationary.

Obviously, with the jaw clutch engaged, the overrunning clutch will be in engagement when the drum 17 is rotating in a direction to unwind the cable 20, but the overrunning clutch will be rotated freely without engagement of the brake when the drum 17 is being driven in a direction to wind up the cable and raise the empty block. In this way the viscous hydraulic fluid in the brake will absorb the greater part of the energy of free fall of the load into the well and will cause a controlled and even descent of the drill stem without destructive wear on the braking and clutching parts. The final stopping of the descent of the load when a stand of pipe is lowered is effected by the usual manually controlled brakes, certain bands of which are indicated at 17' in Figures 1 and 2.

Of course, when the string is being raised from the well, the jaw clutch will be disengaged, thus disconnecting the hydraulic brake and the one-way or overrunning clutch from the drum shaft completely. In this way, the hoisting machinery will be relieved of wear and tear and the useless dissipation of power which would be necessary to wind the cable against the resistance of the hydraulic braking mechanism, and also the empty travelling block will descend by its own weight.

Various changes and modifications may be made in the embodiment illustrated and described herein without departing from the scope of the invention as defined by the following claims.

Having thus described the invention, what is claimed as new and desired to be secured by Letters Patent is:

1. In a well drilling rig of the class described, in combination, a supporting base, a hoist drum, a drum shaft upon which said drum is fixed, bearings on said supporting base for said drum shaft, a retarding braking mechanism for said shaft also mounted on said supporting base, a rotor forming a part of said braking mechanism, a brake shaft upon which said rotor is fixed, said brake shaft being in axial alignment with said drum shaft, a jaw clutch carried by said drum shaft, one element thereof being rotatable on the end of said shaft and the mating element splined on said drum shaft for rotation therewith, and manual means for engaging and disengaging said jaw elements, an automatic one-way driving coupling carried upon said brake shaft, an inner member thereof being fixed on said brake shaft and provided with a peripheral series of inclined cam surfaces, an outer substantially annular

member of said coupling which is concentric with said inner member and provided with a smooth cylindrical bore, and a circular series of spaced rollers disposed between said members, one roller being allotted to each of said cam surfaces, and means connecting said outer coupling member with the first named jaw clutch element on the drum shaft.

2. In a rotary drilling rig for raising and lowering drill pipe and the like in the bore hole of a well, in combination, a hoisting cable, a hoist drum, means for driving said drum in the direction to wind the cable on the drum, a drum shaft on which the drum is fixed, a retarding brake mechanism adjacent said drum, said brake mechanism including a brake shaft and a rotor fixed upon said brake shaft, means supporting said shafts for rotation in substantial axial alignment with projecting end portions of said shafts

10 directed toward each other but spaced apart, and a coupling device adapted to effect disengageable driving connections between said shafts; said device having hollow cupped ends each adapted to envelop and receive a respective end of one

20 of said shafts, a rotary bearing operatively disposed between the periphery of the end portion of the drum shaft and the hollow end of the coupling device which receives it, a jaw clutch element rigid with said hollow end, a sliding jaw clutch element splined on the drum shaft, and manual means for moving said last named clutch element into and out of engagement with said

25 first named jaw clutch element, a one-way overrunning clutch means operatively disposed between the periphery of the brake shaft end portion and the hollow end of the coupling device surrounding it; whereby an operator may completely disconnect the brake shaft from the drum shaft for rotation of the latter free of the retarding brake mechanism in both directions, or

30 connect the two shafts through the positive clutch means while the one-way automatic clutch connects the shafts so that the drum must drive the brake when rotating in one direction but will rotate free and unimpeded by the brake in the

35 opposite direction.

3. In a rotary drilling rig for raising and lowering drill pipe and the like in the bore hole of a well, in combination, a hoisting cable, a hoist drum, means for driving said drum in the direction to wind the cable on the drum, a drum shaft on which the drum is fixed, a retarding brake mechanism adjacent said drum, said brake mechanism including a brake shaft and a rotor fixed upon said brake shaft, means supporting said

40 shafts for rotation in substantial axial alignment with projecting end portions of said shafts directed toward each other but spaced apart, and a coupling device adapted to effect flexible and disengageable driving connections between said

45 shafts; said device having hollow cupped ends each adapted to envelop and receive a respective end of one of said shafts, said device being axially immovable with respect to said shafts, an anti-friction bearing operatively disposed between the

50 periphery of the end portion of the drum shaft and the hollow end of the coupling device which receives it, a jaw clutch element rigid with said hollow end, a sliding jaw clutch element splined on the drum shaft, and manual means for moving

55 said last named clutch element into and out of engagement with said first named jaw clutch element, a one-way overrunning clutch means operatively disposed between the periphery of the brake shaft end portion and the hollow end

60 of the coupling device surrounding it; whereby

65 a coupling device having hollow cupped ends each adapted to envelop and receive a respective end of one of said shafts, said device being axially immovable with respect to said shafts, an anti-friction bearing operatively disposed between the

70 periphery of the end portion of the drum shaft and the hollow end of the coupling device which receives it, a jaw clutch element rigid with said hollow end, a sliding jaw clutch element splined on the drum shaft, and manual means for moving

75 said last named clutch element into and out of engagement with said first named jaw clutch element, a one-way overrunning clutch means operatively disposed between the periphery of the brake shaft end portion and the hollow end

of the coupling device surrounding it; whereby

an operator may completely disconnect the brake shaft from the drum shaft for rotation of the latter free of the retarding brake mechanism in both directions, or connect the two shafts through the positive clutch means while the one-way automatic clutch connects the shafts so that the drum must drive the brake when rotating in one direction but will rotate free and unimpeded by the brake in the opposite direction; the intermediate portion of said coupling device being provided with a flexible joint whereby minor fortuitous misalignments of the two shafts may be accommodated.

4. In a well drilling rig of the class described, in combination, a supporting base, a hoist drum, a drum shaft upon which said drum is fixed, bearings on said supporting base for said drum shaft, a retarding braking mechanism for said shaft also mounted on said supporting base, a rotor forming a part of said braking mechanism, a brake shaft upon which said rotor is fixed, said brake shaft being in axial alignment with said drum shaft, a jaw clutch carried by said drum shaft, one element thereof being rotatable on the end of said shaft and the mating element keyed on said drum shaft for rotation therewith, and manual means for engaging and disengaging said jaw elements, an automatic one-way driving coupling carried by said brake shaft, an inner

substantially annular member of said coupling being fixed on said brake shaft and provided with an outer surface, an outer substantially annular member of said coupling which is concentric with said inner member and provided with an inner surface surrounding and spaced peripherally from the outer surface of the inner annular member, and at least one lock element disposed between said surfaces, the surfaces of said members and of said last-named element being so constructed and arranged that the said coupling members are locked in driving relationship upon rotation of the coupling in one direction, and means connecting said outer coupling member with the first named jaw clutch element on the drum shaft.
